[57] CLAIM

The ornamental design for decalcomania for china dinnerware, as shown and described.

DESCRIPTION

FIG. 1 is a plan view of decalcomania for china dinnerware or similar articles showing a first embodiment of my new design;

FIG. 2 is a plan view of a decalcomania for china dinnerware or similar articles showing a second embodiment of my new design;

FIG. 3 is a plan view of decalcomania for china dinnerware or similar articles showing a third embodiment of my new design;

FIG. 4 is a plan view of decalcomania for china dinnerware or similar articles showing a fourth embodiment of my new design;

FIG. 5 is a plan view of decalcomania for china dinnerware or similar articles showing a fifth embodiment of my new design; and,

FIG. 6 is a plan view of decalcomania for china dinnerware or similar articles showing a sixth embodiment of my new design.

The fragmentary broken line showing of Chinaware is illustrative of environmental structure only and forms no part of the claimed design; the decalcomania is of no substantial thickness.

FIG. 1

FIG. 2

FIG. 3
